UNITED STATES PATENT OFFICE.

CARL H. JOHNSON, OF TAYLORSVILLE, PENNSYLVANIA.

HOSE-CO尤PLING.

1,245,108.

Specification of Letters Patent. Patented Oct. 30, 1917.

Application filed January 5, 1917. Serial No. 140,805.

To all whom it may concern:

Be it known that I, CARL H. JOHNSON, a citizen of the United States, residing at Taylorsville, in the county of Bucks and State of Pennsylvania, have invented new and useful Improvements in Hose-Couplings, of which the following is a specification.

This invention relates to pipe couplings, and more especially to those for train pipes 10 which are operated by hand at times; and the object of the same is to produce a structure wherein the several fluid carrying pipes of a train are thrown into communication automatically when two cars are coupled together, and their valves opened automatically, but means are present whereby these valves may be closed by hand at this time. Also the invention contemplates the provision of means whereby when the cars are 20 uncoupled and the valves in the pipes have closed automatically, they may be opened by hand when desired.

The invention consists in the details hereinafter more fully described and claimed, 25 and shown in the drawings wherein:

Figure 1 is a side elevation of a portion of the meeting ends of two cars and their couplings, showing them equipped with a pair of my improved hose couplings whose 30 heads have just met; and

Fig. 2 is a similar view when the cars have approached closer, the springs in this view being in section.

Fig. 3 is an end view of a car equipped 35 with my coupling, the car-coupling being in section; and

Fig. 4 is a plan view of the same with the draw bar of the car-coupling broken away and the heads of two of my couplings in 40 horizontal section.

Fig. 5 is a perspective detail of one of the loops yet to be referred to.

In Figs. 1 and 2 are shown in outline only the platforms P of two cars, their draw bars 45 B and coupling heads H, and it is directly below these draw bars and heads that I locate the structure constituting my invention. Carried by and depending from its draw bar B is a hanger 1 having a tubular 50 guide 2 in which slides a stem 3 carrying a ball 4 at its front end, and a spring 5 bears the ball normally forward and draws the stem through the guide until a pin 6 contacts with the rear side of the hanger 1. The number 55 7 designates the head of my hose coupling, the same having a socket 8 loosely

embracing the ball 4 so that it may move on it, and the front end of this head has a projection and a recess to match a corresponding recess and projection on the companion head as best seen in Fig. 4. The mating faces of the two heads are provided with openings 9 which register when the heads engage each other, and in Figs. 1 and 2 I have made provision for three of these 60 openings which are connected respectively with sections of hose 10, 11 and 12 or other flexible connectors leading backward and upward and each to its train pipe T, which latter are for conveying steam, hot air, or 65 other fluids as usual. At the point of connection of each hose with its pipe there is a valve 13 whose stem 14 projects forward as best seen in Fig. 4, and a spring 15 shown in dotted lines in this view is intended to 70 hold the valve normally closed. When this stem is pressed to the rear, however, the valve is opened and fluid may flow from the pipe T through the hose to the coupling head, wherein it passes through the mating 75 openings 9 into the hose and thence into the pipe of the other car as is clearly understood. This much of my invention therefore comprises the draw bars and heads of the mating couplers and the connection between the several openings in their heads 80 and the respective train pipes. Each draw bar or stem 3 directly underlies the draw bar D of the car-coupling, is supported by it, and swings from side to side with it as 85 the train turns curves and passes switches; and yet the heads 7 of the hose coupler are projected by springs 5 independent of those on the draw bar D of the car coupler. The latter may be of any suitable type, automatic or otherwise, and is shown in the drawings merely to give an idea of the relative position which my invention occupies 90 with reference thereto.

Depending from the car platform or some 100 other fixed support are two brackets or two pairs of hangers 20 standing on opposite sides of the draw bar D as best seen in Fig. 3, and each carries a horizontally disposed loop whose details are best illustrated in Fig. 5. 105 This loop has its body 21 elongated longitudinally of the car and open transversely thereof, and its size is such that it will accommodate the parts next to be described. Within its rear end is a coiled expansive 110 spring 22. Next forward of the spring there passes through the loop the reduced portion

- 23 of a transverse bar 24, the same being shown in Fig. 4 as having a dropped center 25 passing beneath the draw bar D and permitting the lateral swing of the latter; and 5 beyond it the bar 24 continues onward and through the other loop 21 forward of its spring. At suitable points this bar carries brackets 26 projecting from its front edge, and in each bracket is journaled a roller 27.
- 10 Through the front end of the loop passes another bar or push rod 34 which also has a dropped center 35 loosely embracing the draw bar D, and is also continued across and through the opposite loop, and this bar or 15 rod has handles 36 at its extremities disposed within convenient reach of an operator standing on the ground at either side of the track or who perhaps may descend the car steps part way to reach the same. At proper 20 points to one side of the loops the rod 34 is bowed forward as indicated at 37, the rear and dished side of each bow co-acting with the roller 27 and the bar 24 at times, and the forward side of each bow constituting a cam 25 to co-act with the front end of the loop at times as explained below. The reduced portion 23 of the bar 24 is to prevent the longitudinal movement of this bar through the loops in either direction, whereas the other 30 bar or rod 34 is purposely so shaped that it may be moved longitudinally through the loops by either of its handles 36. The rear-most bar 24 passes across the outer ends of the valve stems 14 as best seen in Fig. 4.
- 35 Rigidly secured at 40 to the rear end of the stem 3 is a yoke whose arms 41 are led forward and upward and are loosely engaged with the front bar or rod 34 in any suitable manner. In Figs. 3 and 4 I have shown this 40 bar as provided with slots 42 with which the hooked front ends of the yoke-arms engage slidably by means of pins or bolts 43, but any equivalent construction may be adopted. The purpose of this detail is in order that, 45 when the stem 3 is pressed to the rear by the meeting of two heads 7 and the compression of the springs 5, the yoke will move to the rear with it and its arms will cause the bar or rod 34 to move to the rear; and contact 50 of this bar or rod with the rollers 27 causes the other bar 24 to move to the rear against the tension of the springs 22.
- The operation of my device will now be clear. When two cars meet and are coupled, 55 as described and the bars 24 move to the rear, they press on the valve stems 14 and open all the valves 13 so that fluid flows from the pipes T through the several hose sections 10, 11 and 12, through the registering ports or 60 passages 9 in the two heads 7, and into the hose sections and pipes of the next car. While the cars are coupled, if it should be desired to close the valves it is only necessary to grasp one of the handles 36 and move 65 the bar or rod 34 in a direction to bring its bows 37 opposite the rollers 27; this permits the bar 24 to move forward under the impulse of its springs 22, with the result that the stems 14 are moved forward under the impulse of their springs 15 and the several 70 valves 13 are closed. When the cars are uncoupled the entire coupling moves forward, the yoke moves forward with the stem, and the bars 34 and 24 move forward so that the valves are automatically closed as just described. If now it should happen that it is desired to open the valves on a car which is uncoupled, the bar or rod 34 is moved by either of its handles to bring the forward 75 faces of its bowed portions 37 into loops 11, 80 with the result that this rod is borne to the rear and, through the rollers 37, moves the bar or rod 24 to the rear and opens the valves. Normally, however, the valves will stand closed when the cars are disconnected 85 and the valves will be automatically opened in the act of connecting the cars, and this is what is desired with the train pipes of all cars. By my invention it will be seen that when a different condition with respect to 90 the valves is desired, it may be brought about by manipulation of the push rod 34 in the proper direction. Manifestly the particular type of valves used at 13 and the specific shape of the faces of the two heads 7 are not 95 essential to the successful operation of this invention. In this respect as well as in others I claim the right to make such changes in details, and in the proportions and materials of parts, as will fall within the scope 100 of the appended claims.
- What is claimed as new is:
1. In a hose coupling for train pipes, the combination with the coupler head and stem, a guide for permitting longitudinal movements thereof, a spring bearing the head normally forward, the train pipes, hose sections leading from the head and connected with said pipes, and independent valves at their points of connection; of guides beneath the car body, a cross bar movably mounted in said guides and extending across the stems of said valves, springs bearing the cross bar normally forward, and means connected with the stem of the hose coupler for bearing said bar to the rear to open all 105 valves when coupling is effected.
2. In a hose coupling for train pipes, the combination with the coupler head and stem, a guide for permitting longitudinal movements thereof, a spring bearing the head normally forward, the train pipes, hose sections leading from the head and connected with said pipes, and independent valves at their points of connection; of guides beneath 110 the car body, a cross bar movably mounted in said guides and extending across the stems of said valves, a yoke whose center is connected with the stem of the coupler, and connections between its arms and said bar 115 120
- 125 130

for moving the latter to the rear to open all valves when coupling is effected.

3. In a hose coupling for train pipes, the combination with the coupler head and stem, 5 means for permitting longitudinal movements thereof, the train pipes connected with the head, and independent valves in said pipes; of loops extending longitudinally beneath the car body, a cross bar movably 10 mounted therein and extending across the stems of said valves, springs bearing the cross bar normally forward, a second bar longitudinally movable through said loops forward of the first bar, cam connections be- 15 tween these bars whereby longitudinal movement of the second bar produces transverse movement of the first bar, and connections between the second bar and the coupler whereby said bar is moved to the rear when 20 coupling is effected.

4. In a hose coupling for train pipes, the combination with the coupler head and stem, means for permitting longitudinal movements thereof, the train pipes, hose sections 25 connecting the head with said pipes, and independent valves in the latter; of guides beneath the car body, a cross bar movably mounted in said guides and extending across the stems of said valves, springs bearing the 30 cross bar normally forward, a second bar longitudinally movable through said guides forward of the first bar, means for preventing longitudinal movement of the first bar, cam connections between these bars whereby 35 longitudinal movement of the second bar produces transverse movement of the first bar, and connections between the second bar and the stem of the coupler whereby said bar is moved to the rear when coupling is 40 effected.

5. In a hose coupling for train pipes, the combination with the coupler head whose stem is movably mounted, the train pipe, a flexible connection between said head and 45 pipe, and a normally closed valve in the pipe whose stem projects forward thereof; of longitudinal loops carried by the car body, a cross bar having reduced portions mounted in said loops whereby it may move 50 therein transversely of its length, a second cross bar longitudinally movable through said loops and bowed forward at one side of each of them and having handles at its extremities, rollers carried by the first-named 55 cross bar at points to register with said bows in the second, this bar passing across the valve-stem, and means pressing it normally forward within said loops.

6. In a hose coupling for train pipes, the 60 combination with the coupler head whose stem is movably mounted, the train pipe, a flexible connection between said head and

pipe, and a normally closed valve in the pipe whose stem projects forward thereof; of longitudinal loops carried by the car body, a 65 cross bar having reduced portions mounted in said loops whereby it may move therein transversely of its length, this bar having a dropped center underlying the draw bar of the car-coupling, a second cross bar lon- 70 gitudinally movable through said loops and bowed forward at one side of each of them and having handles at its extremities, this bar having a dropped center underlying the draw bar of the car-coupling, brackets pro- 75 jecting forward from the first-named cross bar and spaced to correspond with the spacing of said loops, rollers carried by said brackets, this bar passing across the valve- 80 stem, and means pressing it normally for- ward within said loops.

7. In a device of the class described, the combination with the train pipe, a normally closed valve therein whose stem projects toward the end of the car, and a hose coupling whose head is connected with said pipe forward of the valve; of two parallel bars, guide loops supporting them transversely beneath the car platform with the inner bar extending across the valve-stem, 90 means for preventing the longitudinal movement of this bar in its guides, means for pressing it normally forward therein, and cam connections whereby longitudinal movement of the other bar in one direction per- 95 mits the forward movement of the first-named bar, and longitudinal movement in the other direction moves both bars to the rear, for the purpose set forth.

8. In a device of the class described, the combination with the train pipe, a normally closed valve therein whose stem projects toward the end of the car, and a hose coupling whose head is connected with said pipe forward of the valve; of two parallel 105 bars, guide loops supporting them transversely beneath the car platform with the inner bar extending across the valve-stem, means for preventing the longitudinal movement of this bar in its guides, means for 110 pressing it normally forward therein, rollers carried by the forward side of the rear-most bar at one side of said guide loops, and forwardly bent portions on the other bar spaced to correspond with the spacing of 115 the rollers whereby when this bar is moved in one direction the bows register with the rollers and the other bar may move forward whereas when it is moved in the opposite direction the bows are drawn into the guide 120 loops and both bars are pressed rearward, for the purpose set forth.

In testimony whereof I affix my signature.
CARL H. JOHNSON.
